UNITED STATES PATENT OFFICE.

JOHN F. GRACE, OF NEW YORK, N. Y., ASSIGNOR TO HENRY R. WORTHINGTON, A CORPORATION OF NEW JERSEY.

COOLING-TOWER.

1,142,809.

Specification of Letters Patent. Patented June 15, 1915.

Application filed March 7, 1913. Serial No. 752,604.

To all whom it may concern:

Be it known that I, JOHN F. GRACE, a citizen of the United States, residing at New York city, county of Kings, and State of 5 New York, have invented certain new and useful Improvements in Cooling-Towers, fully described and represented in the following specification and the accompanying drawings, forming a part of the same.

10 This invention relates to towers of that class used for cooling towers, air coolers and similar purposes, in which a filling is used to aid the exchange of heat between a liquid trickling downward over the filling 15 and an air or gas current traveling upward, the invention being intended especially for use in large cooling towers such as are now used for cooling the water of condensation in large steam plants.

20 The especial objects of the invention are to provide an improved construction by which the inner side of the shell and interior frame work shall be readily accessible for painting, repair, and other purposes, and 25 to provide an improved board filling by which the boards shall be held securely in position without nailing.

20 The invention includes, also, certain specific features, as hereinafter described and 30 claimed.

35 In the accompanying drawings, forming a part of this specification, there is shown a cooling tower embodying all the features of the invention in their preferred form, and this construction will now be described in detail, and the features forming the invention then specifically pointed out in the 40 claims.

40 In the drawings, Figure 1 is a vertical central section of the lower or filling portion of the tower. Fig. 2 is a detail plan view of a portion of the tower on the line 2 of Fig. 1, showing the filling in place. Fig. 3 is a side elevation of a portion of the 45 tower, showing the doors closed. Fig. 4 is a vertical section of a portion of the tower and filling on the line 4 of Fig. 2. Fig. 5 is a detail section of the filling looking to the left in Fig. 4. Fig. 6 is a detail cross 50 section of a portion of the shell showing the doors open.

55 Referring to the drawings, the cooling tower is shown as of the common circular form, A being the shell or tower proper, the lower portion of which incloses the fill-

ing and the upper portion forms the chimney in natural draft use, this shell being supported on the foundation B above the well C which receives the tower discharge. Above the well C is the air admission space 60 below the filling through which air is forced in by the fans D, of which two are shown, or air is drawn in by natural draft. The air from the fans is preferably guided upward to the filling so as to be distributed 65 therethrough by the curved guides 10, and the air admission space of the tower is preferably provided with doors E on opposite sides of the tower closing openings 11, by which large space for the admission of air 70 is provided by opening the doors, when it is desired to use the construction as a natural draft tower, and which doors give convenient access to the tower below the filling. These doors are preferably arranged in 75 pairs, as shown, swinging in opposite directions, and with the doors of each pair adapted to be secured together when fully open so as to form guides for directing the air into the tower, as shown in Fig. 6, thus 80 securing better air distribution. The usual liquid pipe distributor F, connected to the central supply pipe G, is shown.

Referring now to the filling portion of the tower, the filling is made in two parts, 85 the main filling occupying the main portion of the tower being permanent and fixed in place, as usual in such towers, but being surrounded by a separate filling made removable, so that the space occupied by this 90 removable filling may be utilized, when desired, for access to the inner side of the shell and interior frame of the tower, thus avoiding the serious objection to such cooling towers as previously constructed, that 95 the inner side of the shell and interior frame work are not accessible for painting or repair without the expensive removal and replacement of the tower filling.

In the construction shown, the main filling occupying the greater part of the filling portion of the tower is formed of boards a arranged edgewise with alternate layers crossing each other, as usual in such constructions, this board filling being shown as 100 supported by a series of heavier boards b resting on channel irons or I-beams 12 extending across the tower and supported in any suitable manner. This portion of the filling, as shown, is the same as previously 105 110

used, except that the boards are held in place and their falling down prevented by locking boards *c* extending diagonally across the spaces between the successive series of boards *a* and fitting tightly in the spaces so as to lock the filling boards in position without nailing. These locking boards *c* are inserted vertically, and are shown as each extending vertically through four series of boards *a*, but it will be understood that these locking boards may be of any convenient length.

The removable filling next the shell, is preferably formed, as shown, of vertical boards *d* extending from the top to the bottom of the filling in one length and suspended by cross bars 13 extending across the removable filling space and supported by bars 14, 15, shown as angle irons, the bars 14 being secured to the inner side of the shell and the bars 15 being the top bars of the frame work surrounding the inner filling and supporting the shell, this frame work consisting of vertical and horizontal bars 15, arranged on opposite sides of the removable filling space and secured together by cross braces 16. The boards *d* may thus be removed readily from any part or the whole of the space surrounding the main filling. The liquid dropping from the removable filling *d* is preferably delivered inward to the central part of the tower by trough 17. It will be seen that this filling *d* provides ample space for convenient access to the interior of the shell and tower frame work, throughout the filling portion of the tower, so that the main filling need not be disturbed for re-painting or other repair, but it is necessary only to remove the filling *d* from the portion of the tower to which access is desired either by moving the filling sidewise within the tower or wholly or partially withdrawing it from the tower. By lifting the bars 13 and attached boards *d* sufficiently to release the bars 13 from the supports 14, 15, the boards *d* may be moved sidewise so as to leave open spaces within the casing *A*, as required, or the boards *d* may be lifted wholly or partially out of the tower, if desired for any purpose.

While the filling is preferably wooden boards, as described, it will be understood that these may be sheets or plates of other suitable material, and the term boards is in-

tended to cover such modifications. Moreover, the feature of combining an inner fixed filling with an outer removable filling may be embodied in cooling towers using any form of filling, in place of the board filling shown, many different forms of filling, such as hollow pipe or tile, metal plates, chains and nettings being of common use in such cooling towers, and this feature of the invention, considered broadly, is not limited to the particular form or arrangement of filling shown.

While a combined forced and natural draft tower is illustrated, it will be understood that the features of the invention relating to the filling of the tower are equally applicable to all forms of cooling or similar towers.

What I claim is:

1. A tower of the class described, comprising a tower shell, a fixed inner filling and a removable outer filling surrounding the inner filling and arranged to provide by its removal access to the inner side of the tower shell.

2. A tower of the class described, comprising a tower shell, a fixed inner filling and an outer filling surrounding the inner filling, said outer filling being suspended from the top of the filling portion of the tower and arranged to be withdrawn upward for removal from the tower to provide space for access to the inner side of the tower shell.

3. A tower of the class described, comprising a tower shell, a fixed inner filling with space surrounding said filling for access to the inner side of the tower shell, and a removable filling in said space consisting of boards *d* suspended separately from the top of the filling portion of the tower.

4. A tower of the class described having a filling composed of boards arranged in series edgewise one upon and crosswise of the other and locking boards extending diagonally through the spaces between cross-
ing boards for holding them in place.

In testimony whereof, I have hereunto set my hand, in the presence of two subscribing witnesses.

JOHN F. GRACE.
